UNITED STATES PATENT OFFICE.

HENRY T. FARNSWORTH, OF GLADE SPRING, VIRGINIA, ASSIGNOR OF
ONE-HALF TO GEORGE N. WERTS, OF ABINGDON, VIRGINIA.

FLUID-MOTIVE-POWER PUMP.

SPECIFICATION forming part of Letters Patent No. 761,366, dated May 31, 1904.

Application filed September 5, 1903. Serial No. 172,158. (No model.)

To all whom it may concern:

Be it known that I, HENRY T. FARNSWORTH, a citizen of the United States, residing at Glade Spring, in the county of Washington and State of Virginia, have invented a new and useful Fluid-Motive-Power Pump, of which the following is a specification.

This invention relates to improvements in fluid-motive-power pumps.

10 The principal object of the invention is to construct a pump in which the pressure or head of one body of water may be employed for the pumping of a portion of the same or of an entirely different body of water to any 15 desired distance and in this connection to so arrange the ram as to entirely separate the two bodies of water or other liquid, so that there will be no danger of intermingling of the two, especially where a large body of comparatively 20 impure water is used for the pumping of spring or other water to a house or barn for drinking or like purposes.

A further object of the invention is to provide a novel form of pump in which positive 25 means are employed for opening and closing the controlling-valve.

A still further object of the invention is to provide a hydraulic pump with a novel form of inlet-valve so arranged with respect to the 30 current of incoming water that the pressure or head of the water cannot interfere with the opening or closing movement of the valve.

A still further object of the invention is to provide a novel form of valve and valve-actuating mechanism in which the escape-valve is yieldably connected to the piston that is 35 operated by the pressure of the water, the parts being so arranged that closing movement of the valve will be opposed by counterwise movement of the piston, and the superior area of the latter finally causing a quick-opening movement of said valve after the exertion of a predetermined strain or force on the yieldable connecting means between the piston and valve.

With these and other objects in view, as will more fully hereinafter appear, the invention consists in the novel construction and arrangement of parts hereinafter described,

illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a longitudinal sectional elevation of a hydraulic pump constructed in accordance with the invention. Fig. 2 is a similar view of the lower portion of the same, showing the parts in different positions. Fig. 3 is a sectional plan view of the device approximately on the line 3 3 of Fig. 1. Fig. 4 is a detail perspective view of the inlet and exhaust valves. Fig. 5 is a view similar to Fig. 1, illustrating a slight modification of the invention.

Similar numerals of reference are employed to indicate corresponding parts throughout the several figures of the drawings.

In the drawings, 1 represents a water-chamber or sluice-box, preferably rectangular in form and provided at one end with an inlet 2 and at the opposite end with an outlet 3. The inlet end is rounded and provided with a threaded opening, into which the inlet-pipe may be secured, while between the inlet end and the water-chamber proper is a dependent partition 5, that occupies the upper half of the space and leaves a substantially rectangular port between the lower portion of the entrance-pipe and the water-box for the passage of the water. The inner face of this partition is preferably rounded on a line struck from the center of a pin or shaft 6, which may be in the form of a bolt, and this pin carries a lever 7, at the outer end of which is a valve 8, the outer surface of the valve being concentric with the axis of the pin and adapted to fit snugly against the curved face of the partition 5, so that it may act freely in closing or opening the water-entrance port. Owing to the curved face of this valve, the thrust-line of the water will be directed to the center of rotation of the valve and the water cannot to any material extent impede the free movement of said valve.

The outlet 3 is somewhat contracted in area, having inclined walls 9 and 9', which gradu-

ally converge inward from the outlet end to form a substantially rectangular port in an inclined wall 10. This port is closed by a valve 12, carried by an arm 13 of the lever 7, and 5 the face of the valve is provided with a covering 14, formed of leather or some similar material. The two valves 8 and 12 are so arranged with respect to each other that when one is open the other will be closed, and the 10 inclination of the valve 12 is such that the water will act to better advantage in keeping the valve closed than if said valve were arranged in a direct vertical line.

Secured to the casing and water-chamber is 15 a cylinder 16, the upper end of which has a threaded boss 17 for the reception of a smaller cylinder 18, the latter having internal threads adapted to the boss. The upper end of the cylinder 18 terminates in a T-shaped head, and to 20 one branch of the T is connected an inlet-pipe 19, having an upwardly-opening check-valve 20, while connected to the opposite branch of the T is an outlet-pipe 21, having an upwardly-opening check-valve 22.

25 In the cylinder 16 is arranged a piston 24, the periphery of which is curved for the reception of a ring 25, formed of leather or other packing material, and a split ring 26, preferably formed of spring metal. The 30 split ring serves to maintain the packing-ring in the full out position in contact with the outer wall of the cylinder and will to some extent automatically compensate for wear of the packing-ring. The packing-rings are held 35 in place by a metallic ring 27, bolted or secured in like manner to the head of the piston.

The piston 24 is provided with a hollow stem 30, the upper end of which has a threaded connection with a piston-rod 31, that extends 40 up through an opening of suitable diameter formed in the top of the cylinder 16 and at its extreme upper end has a threaded connection with a small plunger or piston 32, disposed within the cylinder 18. The construction 45 of the plunger may be altered to accommodate varying conditions; but I have found that a preferred form of piston consists in providing the rod with a ring 33, that rests on a shoulder 34 near the upper end of the piston-rod, and then placing on the threaded end 50 of the rod a main piston-body 35 of approximately the same character as the larger piston already described.

The lower end of the piston-rod is provided 55 with a second set of threads to which is secured a spring sleeve or casing 36, carrying a coiled tension-spring 37, the upper end of which is secured to the upper portion of the sleeve or casing, while the lower end of said 60 spring is connected to the valve-carrying arm 13 at a point intermediate of its length.

In the operation of the device, the parts being 65 in the position shown in Fig. 1, water is allowed to flow through the open inlet-port and maintains the outlet-valve 12 closed. The

piston is gradually raised and any water or other fluid which may have been drawn into the cylinder 18 is ejected past the check-valve 22, the down-closing check-valve 20 being closed under the pressure. The water in the 70 lower chamber and the cylinder acts in two directions and tends to keep the valve 12 closed and at the same time to elevate the piston. Owing to the superior area of the latter, the spring will be gradually placed under increased tension until it overcomes the 75 pressure of the water on the valve, and the valve will open suddenly, allowing the water within the cylinder and water-chamber to flow freely through the discharge-pipe. The 80 opening movement of the valve 12 has caused a corresponding closing movement of the valve 8, so that no water can enter the chamber 1 until the piston in traveling downward decreases the length of the spring and by 85 gradually compressing the same forces the valve 12 to closed position and at the same time opens the inlet-valve. The water again enters through the inlet-port, and the same 90 operation is completed. The upper cylinder 90 18 and its piston act as a suction and force pump, and the water pumped through pipe 21 to the point of consumption may be either a portion that actuates the ram or a distinct body of water, so that water from a spring 95 or other minimum source of supply may be pumped without waste to a house or other point by means of a running stream of impure water.

The construction may be slightly modified 100 in the manner illustrated in Fig. 5 by placing the spring at a point wholly above the piston. In this figure the corresponding parts bear reference-numerals similar to those in Fig. 1. A spring 37' is arranged in a casing 36', having one end secured to the upper portion of the piston 24 and its upper end connected to the plunger of the pumping-cylinder. The lever 13 is connected to a rod 40, extending 105 up through the compression-spring 37'. At 110 the upper end of this rod is an enlarged collar or flange 41, with which the upper end of the spring comes into contact when the piston has been raised for a part of its stroke. On upward movement of the piston the spring is 115 compressed and finally overcomes the resistance offered by the valve 12. This construction is in some respects preferable to that 120 illustrated in Fig. 1, inasmuch as there is no waste of water and the spring is more effectively protected.

The spring-casing 36' is provided with an opening 42 to permit the drainage of any water which may accumulate in the upper portion of the main cylinder.

Having thus described the invention, what is claimed is—

1. In combination, a casing having inlet and discharge ports, a pivotally-mounted inlet-valve having its seating-face arranged on a 130

curved line concentric with the pivotal axis of the valve, a discharge-valve connected to and movable with the inlet-valve, a piston arranged within the casing and exposed to water-pressure, and a yieldable connection between said piston and the valves.

2. In combination, a casing having inlet and discharge ports, inlet and discharge valves connected for mutual movement, the discharge-valve and its seat being arranged at an angle to both the inlet and the wall of the casing, a pumping-cylinder arranged above the casing, pistons in both the casing and the cylinder, a piston-rod connecting the two pistons, and a 15 spring forming a yieldable connection between the valves and one of said pistons.

3. In combination, a casing forming a water-chamber and having inlet and discharge ends, a partition depending from the upper portion 20 of the inlet end and forming a contracted inlet-port to the chamber, the outlet end having walls converged toward the interior of the chamber and terminating in a port arranged

at an angle to the direction of the inflow of the water, a pivot pin or bolt carried by the 25 casing, an inlet-valve having a curved face for closing the inlet-port, a discharge-valve for closing the discharge-port, a lever mounted on the pivot pin or bolt and carrying both valves, a pair of cylinders arranged one above 30 the other, the larger of said cylinders being connected directly to the water-chamber, a piston on the larger cylinder, a spring connecting said piston to the valve-carrying lever, a plunger arranged in the smaller cylinder, a 35 piston-rod connecting the piston and plunger, and inlet and discharge pipes connected to said smaller cylinder.

In testimony that I claim the foregoing as my own I have hereto affixed my signature in 40 the presence of two witnesses.

HENRY T. FARNSWORTH.
